CLAIM

I claim the ornamental design for a pressure relief valve for use with concrete pumping system, as shown and described.

DESCRIPTION

FIG. 1 front elevational view showing my new design, FIG. 2 is a left side elevational view, it being understood that a right side elevational view is a mirror image hereof; FIG. 3 is a rear elevation view thereof; FIG. 4 is a top plan view thereof; and, FIG. 5 is a bottom plan view thereof.

1 Claim, 5 Drawing Sheets
